UNITED STATES PATENT OFFICE.

PETER S. LARSON, OF BELOIT, WISCONSIN.

SPRING MOTOR.

1,408,365.

Specification of Letters Patent. Patented Feb. 28, 1922.

Application filed January 4, 1921. Serial No. 434,955.

To all whom it may concern:

Be it known that I, PETER S. LARSON, a citizen of the United States, residing at Beloit, in the county of Rock and State of Wisconsin, have invented certain new and useful Improvements in Spring Motors; and I do declare the following to be a full, clear, and exact description of the invention, such as will enable others skilled in the art to 10 which it appertains to make and use the same.

This invention relates broadly to an improved spring motor, but it has more particular reference to a device of this class 15 such as is used in clocks.

Devices of the above class usually include a frame for supporting the train of gears and the other mechanism, and this frame generally includes detachably connected 20 spaced plates between which the above gears and other mechanism is placed. As far as I am aware, it is the general practice, when replacing the main spring, to disassemble the frame. This method of repairing consumes 25 much time and labor and is not only troublesome but is necessarily expensive to all concerned.

In view of the above circumstances, I contemplate employing a novel mechanism 30 supporting frame having a hole formed in one of the plates through which the main spring may be inserted and removed without disturbing any of the parts of the adjacent mechanism or disassembling said frame as is ordinarily done. To insure effective results, I detachably connect one end of the spring to the shaft which it is intended to rotate and the other end of the spring, I 35 detachably connect with an anchor, the latter, by preference, being in the form of a casing for the spring and being removed, as a unit with said spring, through the aforesaid opening.

Another and important feature of the invention is to employ with the above named casing, a novel retaining member therefor which serves to prevent rotation of the casing, serves to prevent outward bulging of the inner convolutions of the spring, and constitutes a bearing for one end of the shaft 50 which the spring rotates.

The above and other advantages and features of the invention will become apparent during the course of the following description.

In the accompanying drawings forming a

part of this specification and in which like numerals are employed to designate like parts throughout the same:

Figure 1 is a side elevational view of a 60 mechanism supporting frame constructed in accordance with this invention, showing the spring and its casing in operative position.

Figure 2 is a sectional view taken on the plane of the line 2—2 of Fig. 1. 65

Figure 3 is a detail view of the spring casing.

Figure 4 is a central section taken through the casing on the plane of the line 4—4 of Fig. 3. 70

Figure 5 is a detail elevational view of the retainer for the casing.

Figure 6 is a section taken through the retainer on the line 6—6 of Fig. 5.

In carrying out the invention, I contemplate employing a supporting frame 1 such as is used to support the train of gears and other mechanism for operating a clock, this frame, as is usual, including the detachably connected vertically disposed spaced supporting plates 2 and 3 respectively. In accordance with my ideas, the plate 3 is formed adjacent its lower edge with one or more relatively large openings 4, and it is through one of these openings that the main spring 5 is inserted and removed. I may state at this point that one opening is for the main spring which actuates the train of gears while the other opening is intended to permit removal and insertion of a similar 90 spring which serves to operate the alarm, this last opening being used when the frame is used with an alarm-clock. As before intimated, the spring 5 is designed to rotate the shaft 6 and it has one of its ends detachably 95 connected with a lug or the like 7 on the shaft, its other end being connected to an anchor 8, preferably in the form of a casing or housing for the spring. The end of the spring connected with this anchor is preferably 100 secured to it through the medium of an inwardly projecting lug 9 carried by the casing. It is understood that the shaft 6 carries a gear, and pawl and ratchet mechanism intended to mesh with the usual train 105 of gears employed. In order that the spring and its casing may be removed through the opening 4 as a unit, to facilitate repairing, I connect it with the plate 3 in such a way that it may be quickly detached from the 110 latter for accomplishing the above end. To this end, the casing, which is preferably cup-

shaped, is equipped at its open end with laterally disposed stop flanges 11 which bear against the plate 3 in the manner shown. It is to be noted that the free ends of the stop flanges are spaced from one another to provide a pair of diametrically opposite notches 12 for reception of the retainer bar 13 which is bolted or otherwise secured to the plate 3. As before indicated, the retainer bar 13 serves to prevent possible rotation of the casing, serves also to prevent possible bulging or displacement of the inner convolutions of the spring and, as it is equipped at its center with a reinforced opening 14, it constitutes a bearing for the adjacent end of the shaft 6. At this point, I may mention that the closed end of the casing 8 is formed with a comparatively large opening 15 for passage of the shaft, this opening 15 being large enough to permit the edge thereof to clear the lug 7 when removing the spring and casing off of the shaft and through the opening 4.

With a mechanism supporting frame of the kind herein shown and described, it will be seen that in case the main spring is broken and it is necessary to replace it, this can be easily and readily done by simply removing the retainer bar 13 and afterward removing the casing 8 and spring through the opening 4. Of course, before the casing and spring can be so removed, it will be necessary to disconnect the inner end of the spring from the anchoring lug 7, the opening 15 in the casing being sufficiently large, as before stated, to permit the edge thereof to clear this lug when removing the casing. Emphasis is to be laid on the fact that with such a construction, the necessary repairs may be made with the smallest possible amount of labor without interfering with any of the adjacent parts of the train of gears or mechanism or without necessitating disassembling of the frame 1 as is ordinarily done. Consequently, the small amount of labor required and time saved will reduce the expense attached to the repairing operation to a minimum. Not only can the spring and casing be easily removed, but they can be just as easily replaced. In practice, I contemplate manufacturing and selling the spring and its casing as a unit so that no possible trouble will be experienced in removing the spring from or replacing it in the casing. I wish it to be understood however that the foregoing statement is not limiting.

A careful consideration of the foregoing description taken in connection with the accompanying drawings is thought to be sufficient to enable persons skilled in the art to which the invention relates to obtain a clear understanding of the same. Therefore, a more lengthy and detailed description is thought unnecessary.

While I have shown and described the invention as being particularly adapted for use in connection with clocks, I wish it to be understood that it may be equally well used with various types of spring motors. Furthermore, while I have shown a particular construction and arrangement of parts for accomplishing the results hereinbefore set forth, I wish it to be understood that various minor changes in the shape, size and arrangement of parts may be resorted to within the scope of the subjoined claims.

I claim:

1. A spring motor for use in clocks comprising a mechanism supporting frame including a plate having an opening therein, a shaft supported by said frame and having one of its ends extending through said opening, a spring having one end detachably connected to said shaft, means to which the other end of the spring is connected, said means and spring being insertible and removable through the aforesaid opening as a unit, and other means for retaining said first named means in operative position, said retaining means including a bearing for that end of the shaft extending through said opening.

2. A spring motor for use in clocks comprising a mechanism supporting frame including spaced plates, one of which is provided with an opening, a shaft having one of its ends supported by one of said plates, its opposite end extending through the opening in said other plate, a spring for imparting rotation to the shaft, having one of its ends detachably connected with the latter, a casing in which said spring is arranged, the opposite end of the latter being detachably connected therewith and the spring and casing being insertible and removable through the aforesaid opening as a unit, whereby the spring can be repaired without disassembling the aforesaid frame, and means extending across the open end of the casing and detachably connected with the frame for retaining said casing in position, said means including a bearing for the adjacent end of the aforesaid shaft.

3. A spring motor for use in clocks comprising a mechanism supporting frame including spaced plates, one of which is provided with an opening, a shaft having one of its ends connected with the remaining plate and its opposite end extending through the opening in the first named plate, a cup-shaped casing extending through said opening and between said plates, having an opening in its bottom through which the shaft extends and being provided with lateral stop flanges bearing against the outer face of the adjacent plate, the ends of said flanges being spaced apart at diametrically opposite points, and a bar extending across the open end of said casing and arranged between the 120

free ends of said flanges, being detachably secured to the adjacent plate of the supporting frame and being provided at its center with a bearing for the adjacent end of the 5 aforesaid shaft, and a spring having its inner end detachably connected with said shaft and its opposite end detachably connected with said casing, being removable with the latter as a unit through the opening in said 10 plate.

4. In combination, a clock mechanism supporting frame including a plate having an opening, a shaft, a spring for rotating the latter having one of its ends connected there- 15 to, a cup-shaped casing for the spring having an opening in its closed end for passage of said shaft, and equipped with stop flanges at open end bearing against the outer face of the aforesaid plate, and a retaining bar 20 for the casing, extending across the open end of the latter and having its ends connected with said plate, being formed at its center with a bearing in which the adjacent end of said shaft is journaled.

5. In combination, a clock mechanism supporting frame including a vertical plate having an opening therein a shaft supported by said frame and having one of its ends extending through said opening, an anchoring 30 lug on the shaft adjacent the last mentioned end, a cup-shaped casing extending through said opening and into the frame, having a central hole formed in its closed end through which said shaft passes, said hole being suffi- 35 ciently large to clear the aforesaid lug when removing or inserting the casing through

said opening, said casing being equipped at its outer open end with stop flanges abutting the outer face of said plate, the ends of said flanges being spaced from each other to provide a pair of diametrically opposite notches, 40 and a retaining bar for the casing extending through said notches and having its ends detachably connected to the aforesaid plate, serving to prevent rotation of said 45 casing, said bar being provided at its center with a bearing in which the adjacent end of said shaft is journaled, and a spring in said casing having one of its ends detachably connected to the aforesaid anchoring lug, its 50 other end being detachably connected with said casing.

6. A spring motor for use in clocks comprising a mechanism supporting frame including a plate having an opening therein, 55 a shaft supported in said frame and having one end extending through said opening, a spring having one end detachably connected to said shaft for imparting rotation to the latter, a casing for the spring provided with 60 a projection constituting an anchor for the opposite end of said spring, said casing and spring being insertible and removable through the aforesaid opening in the plate as a unit, and means for retaining said casing 65 and spring in operative position, said means including a bearing for the adjacent end of said shaft.

In testimony whereof I have hereunto set my hand.

PETER S. LARSON.
